US0D1101612S

(12) **United States Design Patent** (10) **Patent No.:** **US D1,101,612 S**
(45) **Date of Patent:** **** Nov. 11, 2025**

(54) **RETAINING BOX FOR SLIDE FASTENER**

(71) Applicant: **YKK Corporation**, Tokyo (JP)

(72) Inventor: **Yusuke Hosokawa**, Kurobe (JP)

(73) Assignee: **YKK Corporation**, Tokyo (JP)

(**) Term: **15 Years**

(21) Appl. No.: **29/858,769**

(22) Filed: **Nov. 3, 2022**

(30) **Foreign Application Priority Data**

(57) **CLAIM**

The ornamental design for a retaining box for slide fastener as shown and described.

DESCRIPTION

FIG. 1 is a perspective view of a retaining box for slide fastener according to the first embodiment, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
